LABEL APPLYING MECHANISM

George W. von Hofe, Bound Brook, N. J., assignor
to New Jersey Machine Corporation, Hoboken,
N. J., a corporation of New Jersey

Application March 22, 1947, Serial No. 736,571

12 Claims. (Cl. 216—55)

1

The invention relates to labeling machines or the like, and more particularly to improved mechanism for adhesively applying to articles, sheets of material provided with an adhesive coating on one surface, such as, labels, wrappers, etc. The invention can be utilized in the application of sheets provided with coatings of the usual type of adhesives, but is particularly advantageous in the application of sheets provided with a thermooactivatable adhesive coating.

The principal object of the invention is to provide a novel and simple mechanism which is so constructed that it can be readily adapted to the transfer and application to articles of adhesive coated sheets having widely varying surface configurations and dimensions.

Other objects of the invention, as well as the novel features of construction thereof, will appear from the following description when read in connection with the accompanying drawings, in which Fig. 1 is a diagrammatic view, partly in section, illustrating one manner in which the invention may be utilized; Fig. 2 is a vertical sectional view of a suction transfer head embodying the features of the invention; Fig. 3 is a bottom plan view of the sheet applying face of the suction head; Fig. 4 is a vertical sectional view of the sheet applying portion of a modified form of suction head; Fig. 5 is a plan view of another form of control shim which may be employed in the practice of the invention, and Fig. 6 is a vertical sectional view of the applying portion of the suction head in still another form.

The sheet applying machine, as such, may be of any well-known type, such as, the labeling machine described and illustrated in the Von Hofe Patent No. 2,227,816, issued January 7, 1941. In such a machine, there is provided a transfer means for the labels in the form of a suction head which successively carries labels from a source of supply to the labeling applying station of the machine. At the label applying station, the suction head is lowered to apply the label carried thereby to the article, the suction in the head being so controlled, that when the label is disposed on the article, such suction is released. As is shown in Fig. 1 of the drawings, the mechanism for accomplishing this operation may include a carriage 10 which is slidably mounted on a rail 11 and is reciprocated on such rail by mechanism exemplified by the rod 12 and the arm 13, such rod 12 being pivotally connected at 14 with the carriage 10 and at 15 with the arm 13. A member or plunger 16 is mounted on the carriage for vertical reciprocation thereon by suit-

able means in properly timed relation with the associated elements, and at its lower end, carries the transfer device or suction head generally designated 17. In the operation of this mechanism, the carriage 10 is reciprocated on the rail 11 to carry the suction transfer head 17 between the pick-up station 18 where a label is picked up and the label applying station where such label is applied to the article for which it is intended, the article being mounted at such label applying station on a suitable support, such as, for example, the article supporting means designated 19 in Fig. 1 of the drawings. It will be understood that in the operation of this mechanism, the member or plunger 16 is operatively controlled to correspondingly control the operative steps of the suction head 17.

In practicing the present invention, the labels may be any desired form, such as, the bell-shaped form indicated in dotted outline in Fig. 3 of the drawings and may have any desired surface dimensions. The labels may either be fed from a supply stack directly to the label applying station such as is disclosed in my copending application Serial No. 628,481, filed November 14, 1945, now Patent No. 2,489,837, for Art of adhesively attaching labels and other sheets to articles, or connected in the form of a continuous web A which is wound into a roll 21 so that the surfaces thereof to which is applied the thermoplastic adhesive coating, is disposed to the periphery of such roll, as is shown in Fig. 1 of the drawings. In the illustrated form of the invention, the roll 21 is supported by a shaft 22 which is mounted in the machine in any convenient manner to permit the roll 21 to unwind during the operation of the machine. The web A is fed toward the pick-up station 18 in any suitable manner, as by feed rollers 23, 23 operated intermittently in steps dependent upon and corresponding to the longitudinal dimension of the labels. At the pick-up or label transfer station 18, the machine is provided with a support 24 over which the web is fed, as illustrated in Fig. 1 of the drawings, the web being transversely cut by suitable operating means 25, 25 to separate the individual terminal labels A' from the web A. The arrangement and operation of the feeding and cutting mechanism is such that the individual terminal labels A' are deposited on the support 24 in accurate label receiving relation with the suction transfer head 17. When so positioned on the support 24, the thermoplastic coating of the severed label rests on such support and overlies a plurality of perforations or air vents provided in the supporting

surface 26 of the support 24 and communicating with a chamber 27 formed within such support. The chamber 27 is connected by means of a tube 28 with a source of air. Suitable means are provided to control the air supply to the chamber 27 of the support and consequently its exit through the vents in the surface 26 in any suitable manner so as to provide a condition of suction in such chamber after the feed rolls 23, 23 have delivered a label A' to the support 24 and during the period of operation of the cutting members 25, 25 to hold the label A' in position on such support during such operation, and to deliver compressed air into such chamber 27 to blow the deposited label A' into contact with the suction head 17 when the latter is properly positioned in an arrest position just above such label. The suction in the head 17 is controlled by properly timed valving means of any suitable type so that at the time the label is transferred by air pressure from the supporting surface 26 to the suction head 17, suction will be effective in such head to maintain the label A' properly in position thereon and until the latter is deposited on an article.

As is shown more clearly in Fig. 2 of the drawings, the suction head 17 comprises a main body portion or metal plate 30 provided at its lower end with a dove-tailed seat which extends centrally between the ends of the plate and transversely of the suction head's path of travel between the pick-up and labeling applying stations. Formed in the upper surface 31 of the dove-tailed seat is a recess 32 having predetermined dimensions and shape, the same being determined in part by the surface area of the largest label which the head is designed to carry. The recess 32 is connected by a passageway formed in the upper portion of plate 30 to a source of suction which may lead through a passageway provided in the plunger 16. The plate 30 carries a heating device composed of a pair of electrical resistance elements 33, 33 which are connected with a source of electricity by the wires 34 and which are controlled by a thermostat 35 to maintain the plate 30 at a predetermined temperature.

Fitted in the dove-tailed seat of the plate 30 is a dove-tailed metal plate 36 whose lower end of reduced area projects below the bottom surface of the plate 30 and whose upper surface closes the lower open end of the recess 32 to 50 form a suction chamber. Extending through the plate 36 are a multiplicity of transverse, vertically-disposed passageways 37 which are in communication with the suction chamber and which terminate at the lower face of the plate 36. Secured to plate 36, as by bolts 38, 38 is the metal plate 39 against which the label A' is blown at the pick-up station 18 and which carries such label to the applying station. The plate 39 is provided with a plurality of transverse, vertically-disposed passageways 40 which extend therethrough and which are in alignment or registry with the passageways 37 in plate 36. Secured intermediate the metal plates 36 and 39 is a shim 41 made of any suitable metal, such as, aluminum, brass or bronze to enable it to function as a good heat conductor between the plates 36 and 39. The shim 41 is relatively thin, being approximately three-ten thousandths of an inch thick, and is constructed to permit passage of air through only those passageways 37 and 40 which are contained in an area determined by the size and shape of the label A'. In the construction shown in Figs. 2 and 3, this is accomplished by providing the shim 41 with a control cut-out 42 75

having the exact size and configuration of the label A', as is indicated by the bell-shaped area shown in dotted outline in Fig. 3 of the drawings. In the shim 41' shown in Fig. 5 of the drawings, this is accomplished by providing the shim with a multiplicity of perforations 43 which are contained within a bell-shaped area similar in size and configuration to the shape of the label and which are in alignment or registry with those passageways 37 and 40 that are contained within such area.

It will be understood from the foregoing, that the plates 30, 36 and 39 and shim 41 are in heat conducting relation and that the heat of a predetermined temperature created by the resistance elements 33 and thermostat 35 in plate 30 will be transmitted by plate 36 and shim 41 to plate 39. It will be understood also, that the suction produced in the suction chamber formed by plates 30 and 36 will only be effective over that area of the under surface of plate 39 within which are contained the passageways 40 which are not blocked by the shim either because of a central cut-out 42 such as is provided in the shim 41 shown in Figs. 2 or 3 of the drawings, or because of the perforations 43, such as are provided in the shim 41' shown in Fig. 5 of the drawings. On the other hand, those passageways 40 of plate 39 which are outside of such area, will be disconnected from the suction chamber and the passageways 37 in plate 36 by the material of the shim. There is thus provided on the lower or under surface of plate 39, a suction effective area conforming in exact size and configuration to that of the label to be transferred. This area can be readily changed for other labels of different sizes and shapes by either modifying shims 41 and 41', or by substituting for shims 41 or 41', shims having cut-outs or perforated areas conforming in size and configuration to such other labels, it being only necessary to slidably remove the unit composed of plates 36 and 39 and shim 41, remove bolts 38, replace shims 41 or 41' with a new shim, reassemble plates 36 and 39 with the new shim and replace the thus assembled unit on plate 30. Thus, the suction head 17 of this invention can be readily adapted to transfer labels having a wide variety of sizes or shapes simply by providing it with the proper constructed shims. The plate 39 is preferably of a size that its sheet contacting surface has a larger area than the surface area of the largest label which such plate is designed to carry. In order that such plate will effectively perform its functions, it is necessary not only that its suction area be equally effective over all portions of the label, but that the thermoplastic adhesive coating on the label be activated over its active area before the label is applied to the article and during its transfer to such article. It has been found that these results are best accomplished by making the passageways 38 and 40 in plates 36 and 39, respectively, and the apertures in plate 41' as small as possible and as close as possible. Thus, good results were obtained by making such passageways and perforations of fifty-one thousandths of an inch in diameter and spacing them one-quarter of an inch from center to center. By providing a sixteen inch vacuum in the suction chamber between plates 30 and 36 and maintaining the plate 30 heated at a temperature of 270° F., it was found that plates and shim provided with passageways and apertures of the indicated

size and arrangement, would effectively transmit the labels and transform the thermo-activatable adhesive coatings thereof to the desired tackiness within the shortest possible time. With such a construction, at least approximately sixty labels per minute can be applied satisfactorily to articles.

It is believed that an understanding of the operation of the invention will be obtained from the above description, but it might be advisable to point out that when a label A' is blown into contact with the lower face of plate 39, the suction effective at the lower ends of those passageways 40 which are not blocked off by the shim 41, will maintain such label accurately in place on the suction head 17. The carriage 10 is then shifted on the rail 11 to bring the suction head 17 and the label A' held thereon by suction, to the label applying position. During the travel of the suction head 17 to the label applying position, the label is heated by plate 39 to adhesively activate the thermoplastic coating thereon. When the suction head 17 arrives at the label applying station, the member or plunger 16 is moved downwardly on the carriage 10 to bring the label A' with its heat activated thermoplastic coating into surface engagement with the bottle or other article in place on the supporting means 19 at the time. The heat activated condition of the thermoplastic coating of the label causes the label to adhere to the article and at the proper moment the suction in the head 17 is cut off. The action of the head alone may be relied upon to firmly press the label A' into adhesive engagement with the article, or the initial deposit of the label on the article may be followed by pressure applied subsequently to complete the application of the label to the article. After the label has been deposited on the article, the head is raised on the carriage 10 which is then shifted back to the pick-up station 18 in position to pick up another label for transfer to the applying station. Due to the fact that the suction head 17 is heated, it is not brought back into contact with the next label A' on the support 24, but is brought back to a position where it is in spaced recovering relation to such support, as shown in Fig. 1 of the drawings, in position to receive such label on the next discharge of air through the vents of surface 26 of support 24.

While I have hereinabove described preferred forms of the invention, it will be understood by those skilled in the art that various changes in such forms may be made without departing from the spirit of the invention. Thus, instead of positioning the shim 41 between the plates 36 and 39 in the manner shown in Fig. 2 of the drawings, such shim may be placed over the lower face of the plate 39 in the manner shown in Fig. 4 of the drawings. In such latter construction, the shim 45 may be attached to the plate 36' in any suitable manner, as by the bolts 46 and may form a support for the plate 39'. The plate 39' may also be made integral with plate 36' in this form of the invention. Due to the extreme thinness of shim 45, it will function satisfactorily in this construction to transfer the label from the pick-up station to the label applying station in the manner previously described. Fig. 6 shows the plates 36' and 39' made in one integral plate 47 with the shim 45' engaged with the lower face thereof. Fig. 6 also illustrates that the label engaging surface of the head 17 may have any form complementing the surface of the article to which the label is to be applied and in

order that the application of the label to such article surface by the head 17 will be facilitated. Thus, the curved lower surface of the plate 17 and the curved body of the shim 45' will improve the application of the label carried thereby to articles having rounded surfaces, such as bottles. The shim 45 in Fig. 4 and the shim 45' in Fig. 6 may either be provided with a cut-out in the manner of shim 41 or be provided with a multiplicity of perforations in the manner of shim 41', to control the suction effective area on the outer or lower surfaces of such shims. In constructing a shim of the type of shim 41', it is preferred that it be done by first securing the shim in an unperforated form in proper position on the suction head, then placing a label in proper pick-up position on the suction head, and then with the aid of a suitable tool perforating through both the label and the shim to provide in such shim the required perforations in registry with the air passageways which connect the label supporting surface of the suction head with the suction chamber 32 of such head. This simple procedure eliminates the close registry and exactness it would be necessary to exercise in providing such perforations in the shim prior to its assembly on the suction head.

I claim:

1. In a machine for applying adhesive coated sheet material to articles, a suction transfer device having a sheet carrying surface, means adapted to create a suction condition over a certain area of such surface, and selective means on said device for reducing and confining such condition of suction to a portion of said area less than the whole area, but large enough to support the entire sheet.
2. In a machine for applying adhesive coated sheet material to articles, a suction transfer device having a sheet carrying surface, a multiplicity of air passageways terminating at such surface, said passageways being connected to a source of suction and arranged to create a suction condition over a certain area of such surface, and selective means for blocking certain of said passageways so as to confine such condition of suction to a portion of said area less than the whole area.
3. In a machine for applying adhesive coated sheet material to articles, a suction transfer device having a sheet carrying surface and having a chamber connected to a source of suction, a multiplicity of air passageways connecting the suction chamber with said surface and arranged to create a suction condition over a certain area of such surface, and a shim carried by said device and constructed and arranged to block certain of said passageways so as to confine such condition of suction to a portion of said area less than the whole area.
4. In a machine for applying adhesive coated sheet material to articles, a suction transfer device having a sheet carrying surface and having a chamber connected to a source of suction, said chamber overlying said surface and having an area in a plane parallel with said surface approximating the area of such surface, a multiplicity of air passageways connecting the suction chamber with said surface, said passageways being of relatively small diameter and in sufficient number to create a suction condition over a certain area of said surface, and a removable shim carried by said device and constructed and arranged to block certain of said passageways so as to confine such

condition of suction to a portion of said area less than the whole area.

5. In a machine for applying adhesive coated sheet material to articles, a suction transfer device having a sheet carrying surface and comprising a body plate having an enlarged recess connected to a source of suction, a second plate removably connected to said body plate and having an inner surface forming with said recess a suction chamber, a multiplicity of air passageways formed in said second plate and being in communication with such chamber and said sheet carrying surface so as to enable the creation of a suction condition over a certain area of such surface, and a shim in engagement with a surface of said second plate and constructed and arranged to block certain of said passageways so as to confine such condition of suction to a portion of said area less than the whole area.

6. In a machine for applying adhesive coated sheet material to articles, a suction transfer device including a body plate having a dove-tailed seat provided on its inner surface with an enlarged recess connected to a source of suction, a dove-tailed plate removably positioned in the seat of said body plate and having its inner surface forming with said recess a suction chamber, a third plate connected to said dove-tailed plate, said latter two plates having formed therein a multiplicity of aligned air passageways connecting the suction chamber with the outer surface of said third plate so as to enable the creation of a suction condition over a certain area of such outer surface, and a shim positioned intermediate said dove-tailed plate and said third plate and constructed to block certain of said passageways so as to confine such condition of suction to a portion of said area less than the whole area.

7. A machine such as defined in claim 6, in which said body plate, dove-tailed plate and third plate are in heat conductive relation and includes means carried by said body plate for maintaining said plates at a predetermined temperature.

8. In a machine for applying adhesive coated sheet material to articles, a suction transfer device having a sheet carrying surface, said surface being of curved contour and having a certain area, means carried by said device adapted to create a suction condition over a portion of said surface area less than the whole area and sufficient to enable such surface to carry a sheet, and heating means carried by said device for heating said surface and thereby heating the carried sheet.

9. In a machine for applying thermo-activatable adhesive coated sheet material to articles, a suction transfer device having a sheet carrying surface, a multiplicity of air passageways terminating at such surface, said passageways being connected to a source of suction and arranged to create a suction condition over an area of such surface sufficient to support thereon a thermo-activatable adhesive coated sheet to be carried, and means carried by said device for heating said surface and the thermo-activatable adhesive coating on the sheet being carried, said passageways being of such minute diameter and

arranged so closely together on said surface area that the sheet will be effectively held on said surface even though a portion of said passageways are only partially covered by the edges of the sheet, and so that the heat contained in the portions of said surface covered by said sheet will effectively and evenly activate the adhesive coating on the sheet over its entire area.

10. In a machine for applying adhesive coated sheet material to articles, a suction transfer device having a plate providing a sheet carrying surface and having a chamber connected to a source of suction, a multiplicity of air passageways in said plate connecting said surface thereof with the suction chamber and arranged to create a suction condition over a certain area of such surface, and a shim carried by said device and constructed and arranged to block certain of said passageways so as to confine such condition of suction to a portion of said area less than the whole area, said shim being constituted of a relatively thin sheet of metal and containing a plurality of perforations in registry with said air passageways and located within an area of said shim substantially similar in shape to the area of the sheet to be carried.

11. In a machine for applying adhesive coated sheet material to articles, a suction transfer device having a sheet carrying surface and having a chamber connected to a source of suction, a multiplicity of air passageways connecting the suction chamber with said surface and arranged to create a suction condition over a certain area of such surface large enough to support the entire sheet to be carried, and selective means carried by said device and constructed and arranged to block certain of said passageways so as to confine such condition of suction to a portion of said area less than the whole area and having substantially the same size and configuration as such sheet.

12. In a machine for applying adhesive coated sheet material to articles, a suction transfer device having a sheet carrying surface and having a chamber connected to a source of suction, a multiplicity of air passageways connecting the suction chamber with said surface and arranged to create a suction condition over a certain area of such surface large enough to support the entire sheet to be carried, and selective means carried by said device and located thereon intermediate said suction chamber and the sheet to be carried by said device, said selective means being constructed and arranged to block certain of said passageways so as to confine such condition of suction to a portion of said area less than the whole area and having substantially the same size and configuration as such sheet.
